CLAIM

The ornamental design for a shoe as shown and described.

DESCRIPTION

FIG. 1 is a bottom front perspective view of a first embodiment of a shoe showing our new design;

FIG. 2 is a bottom view thereof;

FIG. 3 is a bottom rear perspective view thereof;

FIG. 4 is a bottom front perspective view of a second embodiment of a shoe showing our new design;

FIG. 5 is a bottom view thereof; and,

FIG. 6 is a bottom rear perspective view thereof.

The broken line immediately adjacent to and surrounding the shaded area defines the peripheral bounds of the claimed design and forms no part thereof. In FIGS. 1-3, the broken line square lines on the tread bottoms form no part of the claimed design. The broken lines depicting the remainder of the shoe form no part of the claimed design.
